TUBE FRAME FOR AXMINSTER LOOMS

Filed Dec. 5, 1929

UNITED STATES PATENT OFFICE

OSCAR V. PAYNE, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

TUBE FRAME FOR AXMINSTER LOOMS

Application filed December 5, 1929. Serial No. 411,924.

This invention relates to tube frame hang-
ers such as may be employed in Axminster
looms, and it is the general object of the in-
vention to provide an improved form of chain
5 engaging hook which is slidable on the tube
frame and substantially rigid for the purpose
of affording a durable and strong connection
between the tube frame and its supporting
chain.

10 Tube frames of Axminster looms are or-
dinarily suspended between travelling chains
and are held to them by means of some form
of hook. One by one the tube frames are
released from the chains by means of a pair
15 of clutches which first move inwardly to re-
lease the tube frame and then downwardly
carry the same to cloth forming position.
The chains are trained over a series of sprock-
ets with the result that in certain positions
20 the tube frames hang below and in other posi-
tions are supported above the chains. It is
an important object of my present invention
to provide a connection between the tube
frame and the chain including a slidable hook
25 which has sliding engagement with the sup-
porting bar of the tube frame and is urged
outwardly by a resilient element carried by
the bar.

It is a further object of my present inven-
30 tion to provide the supporting hook with ears
having sliding engagement with the interior
of a tubular bar, said ears being spaced to
provide room for a spring which may if de-
sired be guided by a tongue formed as part of
35 the hook.

It is a further object of my invention to
provide an improved form of sliding rigid
hook or chain engaging latch for my Axmin-
40 ster tube frame.

With these and other objects in view which
will appear as the description proceeds, my
invention resides in the combination and ar-
rangement of parts hereinafter described and
45 set forth in the claims.

In the accompanying drawings wherein a
convenient embodiment of my invention is
set forth,

Fig. 1 is a front elevation of one end of a
tube frame and clutch showing the latter

prior to engagement with the tube frame,
certain parts being in section,

Fig. 2 is a view similar to a portion of Fig.
1 but with the clutch in tube frame support-
ing position,

Fig. 3 is a perspective view of the bracket
which is inserted in the tubular bar,

Fig. 4 is a fragmentary perspective view
of the lower part of the hook member,

Fig. 5 is a detail vertical section on line 60
5-5 of Fig. 1, and

Fig. 6 is a perspective view of the hook
in one stage of its manufacture.

Referring to Figs. 1 and 2, I have shown
a bar 10 preferably tubular and having yarn 65
tubes 11 secured thereto. The tube frame
bracket comprises a spool bearing element
12 to support the spool S and having a hori-
zontal arm 13 extending along the upper
70 wall of the tubular bar and secured thereto
by means of a screw 14. The bracket com-
prises also a chain engaging element 15 hav-
ing a prong 16 to extend between the links 17
of the chain which as shown in Figs. 1 and 2
75 is out of longitudinal alignment with the
tubular bar 10. The lower portion of the
element 15 has an arm 18 which extends into
the tubular bar and is secured thereto by
means of screws 19. The screws 14 and 19
80 are preferably located midway between the
vertical walls of the tube frame for a reason
to be set forth hereinafter, and extend
through offset portions 28 of the arms. A
friction pad 20 carried on the leaf spring 21
85 secured to the tube frame may engage the
head of the spool to resist excess rotation of
the latter.

The clutch C is provided with a vertical
body 22 from the lower portion of which ex-
90 tends a lip 23 having an inwardly and down-
wardly extending cam surface 24. Side
wings 25 on the clutch together with the lip
23 form a pocket to receive the tube frame.
A stud 26 affords means for supporting the
95 clutch on a transferrer arm not shown, while
an upper stud 27 is the means by which the
clutch and tube frame may be rocked around
the stud 26 in the act of forming a row of
tufts.

The matter thus far described is of com-

mon construction and forms no part of my present invention, the bottom of the tube frame usually being slightly lower than the top of the surface 24 so that as the clutch moves inwardly the tube frame will be raised a small amount.

My present invention relates particularly to the chain engaging hook H and I form the latter preferably though not necessarily of a single piece of metal having an upper bent end 30 to extend over one of the links 17 and having a downwardly and somewhat inwardly inclined lifting portion 31. The lower end of the hook is formed with a relatively wide web 32 from the upper and lower portions of which extend pairs of spaced guide ears 33 and 34, respectively. These pairs of ears are parallel and positioned to engage, respectively, the arms 13 and 18, previously described. The screws already referred to lie between the paths of travel of the ears, as shown in Fig. 5.

Projecting centrally with respect to the ears is a tongue 35 substantially parallel to the arms 13 and 18 and having the inner or left hand end as viewed in Fig. 1 slidably mounted through upper and lower notches 36 and 37, respectively, formed in the opposite vertical ends 38 and 39, respectively, formed as integral continuations of the arms secured to the tubular bar.

A compression coil spring 40 surrounds the tongue and is interposed between the ends 38 and 39 at the left and the web 32 at the right as shown in Fig. 1. The effect of the spring is to hold the hook member to the right so that the end 30 may either actually engage or be very close to the prong 16. The parts are preferably so formed that the web 32 under these conditions will also lie against the vertical portion of the chain engaging element 15. The spring is positioned to some extent by the ears and held by them away from the screws and offset portions 28 of the arms.

The clutch C has extending therefrom a stud 41 adapted to pass through a slot 42 formed in the chain engaging element. It is preferable to have the bottom of the slot in engagement with the stud when the parts are in the position shown in Fig. 2. So far as movement of the hook is concerned, I find that it is not necessary to use the stud. The upper portion of the clutch may engage the hook and slide the same in a direction parallel to the bar.

The manner of forming the hook is indicated in Fig. 6, where it will be seen that a strip of sheet metal of substantially the width of the arms 13 and 18 is sheared to form the ears previously described. The upper ears may be of substantial length limited by the distance between the hooked end 30 and the web 32. After shearing the upper pair of ears may be bent around the dot and dash

lines 50, while the lower ears 34 are bent around lines 51. The tongue 35 is bent around the line 52 to lie between the upper and lower ears. The tongue, when bent to position, provides clearance for the lower screws 19 and associated offsets 28, while the lifting portion 31 of the hook, remaining vertical, permits clearance for the upper screw 14 and its offset.

As the clutch is moved in its initial or longitudinal motion toward the tube frame the lip will engage the bottom of the bar to lift it a slight amount for the purpose of relieving the hook of the strain of supporting the tube frame. Continued inward motion of the clutch will bring about a movement of the rigid hook toward the spool until the end 30 is out of vertical alignment with the chain, after which the customary downward motion of the clutch may take place to move the tube frame toward cloth forming position.

It will be noted that the upper ears 33, although lying within the tube frame and vertically supporting the weight of the latter, are nevertheless not far removed from a position of vertical alignment with the chain, and it is these ears which support the weight of the tube frame when hanging from the chain. It will also be seen that the ears are spaced sufficiently to permit the spring 40 to pass therebetween, the spring by reason of this construction being of sufficient length to prevent improper deformation during the releasing operation. Furthermore, it will be seen that the web may be engaged by the stud, although this operation is not necessary. Also, the ears are so placed as to avoid interference with the screws which hold the bracket to the tube frame. I do not wish to be held to the use of the tongue as a necessary aid in guiding the hook as it slides, as the ears may be made long enough to perform this function.

Having thus described my invention it will be seen that changes and modifications may be made therein by those skilled in the art without departing from the spirit and scope of the invention and I do not wish to be limited to the details herein disclosed, but what I claim is:

1. In a tube frame for an Axminster loom operating with a transporting chain, a longitudinal bar out of alignment with the chain, a bracket carried by the bar and having a portion to support a spool and also a portion to engage the chain, a pair of spaced parallel arms formed as parts of the bracket, a rigid hook slidably mounted on the tube frame and having an upwardly extending chain engaging hook by which the tube frame is supported on the chain, said hook having at the lower end thereof spaced guide ears to slide between and be guided by the arms, and resilient means to hold the hook normally in chain engaging position.

2. In a tube frame for an Axminster loom operating with a transporting chain, a longitudinal bar out of alignment with the chain, a bracket carried by the bar and having a portion to support a spool and also a portion to engage the chain, a pair of spaced parallel arms formed as parts of the bracket, a rigid hook slidably mounted on the tube frame and having an upwardly extending portion to overhang the chain to support the tube frame, the lower portion of the hook having spaced horizontal guide ears lying between and having sliding relation with the arms, and resilient means disposed between and positioned by the ears to hold the hook normally in chain engaging position.

3. In a tube frame for an Axminster loom operating with a transporting chain, a longitudinal bar out of alignment with the chain, a bracket carried by the bar and having a portion to support a spool and also a portion to engage the chain, a pair of spaced parallel arms formed as parts of the bracket, a rigid hook slidably mounted on the tube frame and having an upwardly extending portion to overhang the chain to support the tube frame, the lower portion of the hook having spaced horizontal guide ears lying between and having sliding relation with the arms, and resilient means disposed between and positioned by the ears to hold the hook normally in chain engaging position, one end of said resilient means bearing against portions of the arms.

4. In a tube frame for an Axminster loom operating with a transporting chain, a hollow tubular bar out of horizontal alignment with the chain, a bracket having a substantially vertical portion extending across one end of the hollow bar and having also spaced horizontal arms inserted into the hollow bar, and a rigid chain engaging hook extending transversely of the bar into engagement with the chain, said hook extending through the bracket and having guide portions extending into the bar to engage and have sliding relation with the spaced parallel arms, and resilient means to hold the hook normally in engagement with the chain.

5. In a tube frame for an Axminster loom operating with a transporting chain, a hollow tubular bar out of horizontal alignment with the chain, a bracket having a substantially vertical portion extending across one end of the hollow bar and having also spaced horizontal arms inserted into the hollow bar, and a rigid chain engaging hook extending transversely of the bar into engagement with the chain, said hook having guide portions extending into the bar to engage and have sliding relation with the spaced parallel arms, and resilient means to hold the hook normally in engagement with the chain, the lower portion of the hook and guide portions lying within the space defined by the parallel arms

and that portion of the bracket which extends across the end of the hollow bar.

6. In a tube frame for an Axminster loom operating with a transporting chain, a hollow tubular bar out of horizontal alignment with the chain, a bracket having a substantially vertical portion extending across one end of the hollow bar and having also spaced horizontal arms inserted into the hollow bar, and a rigid chain engaging hook extending transversely of the bar into engagement with the chain, said hook having guide portions extending into the bar to engage and have sliding relation with the spaced parallel arms, and resilient means to hold the hook normally in engagement with the chain lying between the guide portions, the lower portion of the hook and guide portions lying within the space defined by the parallel arms and that portion of the bracket which extends across the end of the hollow bar.

7. In a tube frame for an Axminster loom operating with a transporting chain, a hollow tubular bar, a bracket secured to said bar and having a portion extending across the open end of the bar and having other portions extending transversely of the chain, a pair of spaced parallel arms formed as part of the bracket and located within the tube frame, a rigid hook having a lower portion extending into the tube frame and having an upper portion transverse of the bar extending into relation with the chain, that portion of the hook extending within the bar having integral therewith spaced parallel ears having sliding engagement with the parallel arms to guide the hook and cause the same to have a right line motion with respect to the tube frame, and yielding means holding the hook normally in chain engaging position.

8. In a tube frame for an Axminster loom operating with a transporting chain, a hollow tubular bar, a bracket secured to said bar and having a portion extending across the open end of the bar and having other portions extending transversely of the chain, a pair of spaced parallel arms formed as part of the bracket and located within the tube frame, a rigid hook having a portion extending into the tube frame and having another portion extending transversely of the bar into engaging position with the chain, two spaced substantially parallel elements formed integral with the hook extending within the bar and having sliding relation with respect to the arms, and yielding means holding the hook normally in chain engaging position.

9. In a tube frame for an Axminster loom operating with a transporting chain, a hollow bar out of longitudinal alignment with the chain, said tube frame having two spaced fixed parallel surfaces, a rigid hook extending transversely from the bar and having holding engagement with the chain, spaced surfaces rigid with the hook in en-

- gagement with the first named surfaces, the second named surfaces being slidable along the first named surfaces to cause the hook to have a right line motion with respect to the bar in a direction away from the chain, a yielding means resisting said right line motion and normally holding the hook in engaging position relatively to the chain.
10. In a tube frame for an Axminster loom operating with a transporting chain, a longitudinal bar out of alignment with the chain, a bracket carried by the bar and having a portion to support a spool and also a portion to engage the chain, a pair of spaced parallel arms formed as parts of the bracket, a rigid hook having an upwardly projecting portion to engage the chain, said hook having a lower horizontal portion extending between the spaced arms and having sliding engagement therewith, and yielding means to hold the hook normally in engaging relation with the chain.
11. In a tube frame for an Axminster loom having a transporting chain, a hollow bar out of alignment with the chain, a rigid hook having portions slidable along interior surfaces of the bar and having a laterally extending chain engaging part, and yielding means to hold the hook in normal chain engaging position.
12. A latch member for an Axminster tube frame formed of a hollow bar having spaced parallel sliding surfaces, said latch having an upwardly extending chain engaging hook to extend transversely of the bar, and parallel guide surfaces on the hook to extend inside the bar to engage and slide along the spaced parallel surfaces thereon.
13. A rigid supporting hook member for an Axminster tube frame having a longitudinal bar, said hook member having an upwardly extending chain engaging portion to lie over a transporting chain and having at the lower portion thereof spaced ears which are substantially parallel to the bar and disposed on opposite sides of the chain engaging portion to prevent twisting of the latter, the ears causing the latch to have a right line sliding motion.
14. A rigid supporting hook member for an Axminster tube frame having a longitudinal bar, said hook member having an upwardly extending chain engaging portion to lie over a transporting chain and having at the lower portion thereof spaced ears which are substantially parallel to the bar and disposed on opposite sides of the chain engaging portion to prevent twisting of the latter, the ears causing the latch to have a right line sliding motion, and a tongue rigid with the hook member extending between the ears.
15. In a bracket for an Axminster tube frame having a hollow tubular bar, spaced parallel arms to fit within the bar, a hook or latch member slidable on the bracket and having guide portions within the bar to engage and slide along the arms, said latch having a portion extending laterally from the bar to engage the chain.
16. A bracket for an Axminster tube frame having a tubular carrier bar, said bracket being formed of a spool bearing member having an arm extending into and parallel to the bar and having the inner end thereof bent transversely of the bar, said bracket having a chain engaging member having an arm spaced from the first named arm extending within the bar parallel to the latter and having the end thereof bent transversely of the bar, said transverse ends being bent toward each other to define with one of said members a substantially closed loop, a supporting latch to engage a transporting chain having a portion extending outside the loop and transversely of the carrier bar, said latch having another portion extending inside the loop and confined within the latter and having sliding movement along the arms, and resilient means to hold the latch in normal chain engaging position.
17. A bracket for an Axminster tube frame having a tubular carrier bar, said bracket being formed of a spool bearing member having an arm extending into and parallel to the bar and having the inner end thereof extending transversely of the bar, said bracket having a chain engaging member having an arm spaced from the first named arm extending within and parallel to the bar and having the end thereof extending transversely of the bar, said transverse ends being bent toward each other to define with one of said parts a substantially closed loop, a latch to engage a transporting chain having a portion extending outside the loop and another portion extending inside the loop and confined within the latter and having sliding movement along the arms, and resilient means to hold the latch in normal chain engaging position, said members having alignment slots through which a portion of the hook extends.
18. A bracket for an Axminster tube frame having a tubular bar, said bracket having an upwardly extending chain engaging member, an arm formed integral with said member lying within and parallel to the bar and having an upturned end, means rigid with said member defining a second arm spaced from the first arm and lying within and parallel to the bar and having a downturned end, said member, arms, and turned ends forming a substantially closed loop, a rigid latch having a chain engaging portion extending transversely of the bar outside the loop and having integral therewith bearing portions extending through said member into the loop, said portions located within the loop having sliding engagement with the arms, and re-

silient means to hold the hook in normal chain engaging position.

19. A bracket for an Axminster tube frame having a tubular bar, said bracket having an upwardly extending chain engaging member, an arm formed integral with said member lying within and parallel to the bar and having an upturned end, means rigid with said member defining a second arm spaced 5 from the first arm and lying within and parallel to the bar and having a downturned end, said member, arms, and turned ends forming a loop, a rigid latch having a chain engaging portion extending transversely of the bar 10 outside the loop and having integral therewith bearing portions extending through said member into the loop, said bearing portions located within the loop having sliding engagement with the arms, and resilient 15 means to hold the hook in normal chain engaging position, said resilient means being housed within the loop.

20. A bracket for an Axminster tube frame having a tubular bar, said bracket having 25 an upwardly extending chain engaging member, an arm formed integral with said member lying within and parallel to the bar and having an upturned end, means rigid with said member defining a second arm spaced 30 from the first arm and lying within and parallel to the bar and having a downturned end, said member, arms, and turned ends forming a loop, a rigid latch having a chain engaging portion extending transversely of the bar 35 outside the loop and having integral therewith bearing portions extending through said member into the loop, said portions located within the loop having sliding engagement with the arms, resilient means to hold the 40 hook in normal chain engaging position, and a tongue integral with the latch to guide the resilient means, said tongue sliding between the bent ends of the arms.

21. In a tube frame for an Axminster loom 45 operating with a transporting chain, a hollow tubular bar out of longitudinal alignment with the chain, guide means rigid with the bar, a slide element movable on the guide means, a sliding hook rigid with the slide 50 element and extending laterally from the bar to engage the chain, and a resilient member surrounding the sliding element and located in the bar and acting on the sliding element to hold the hook normally in engagement with the chain, the hook deriving its 55 chief support from the sliding element and guide means.

In testimony whereof I have hereunto affixed my signature.

OSCAR V. PAYNE.
